US0D1069004S

(12) **United States Design Patent** (10) Patent No.: **US D1,069,004 S**
(45) Date of Patent: ** Apr. 1, 2025

(54) **DIVOT REPAIR TOOL**

(71) Applicant: **Acushnet Company**, Fairhaven, MA (US)

(72) Inventors: **Don T. Cameron**, Carlsbad, CA (US); **Augustin W. Rollinson**, Del Mar, CA (US)

(73) Assignee: **Acushnet Company**, Fairhaven, MA (US)

(**) Term: **15 Years**

(21) Appl. No.: **29/876,358**

(22) Filed: **May 19, 2023**

(51) LOC (15) Cl. **21-02**

(52) U.S. Cl.

USPC **D21/793**; D21/698; D21/789
